UNITED STATES PATENT OFFICE.

BENJAMIN F. JOHNSON, OF CLEVELAND, OHIO.

PIPE.

1,376,548.

Specification of Letters Patent. Patented May 3, 1921.

Application filed September 22, 1919. Serial No. 325,349.

To all whom it may concern:

Be it known that I, BENJAMIN F. JOHNSON, a citizen of the United States, residing at Cleveland, in the county of Cuyahoga and State of Ohio, have invented a certain new and useful Improvement in Pipes, of which the following is a full, clear, and exact description.

The present invention relates to tobacco smoking pipes, and seeks to provide a construction which provides a well for the collection of saliva which may pass into the pipe from the mouth of the user and prevent the fouling of the pipe.

15 A further object is to construct a pipe as aforesaid, which may be easily cleaned.

A further object is to provide a construction for the purpose which will add little or no weight to a pipe and further, the construction is such as to add very little extra expense in the manufacture.

Generally speaking, the invention may be said to comprise the elements and the combinations thereof, set forth in the accompanying claim.

Reference should be had to the accompanying drawings forming a part of this specification, in which Figure 1 is a sectional elevation of a pipe embodying my invention; Fig. 2 is a section upon the line 2-2 of Fig. 1; Fig. 3 is a section upon the line 3-3 of Fig. 1; Fig. 4 is a section upon the line 4-4 of Fig. 1; Fig. 5 is an elevation with portions in section of a portion 35 of the pipe.

As is well known, a pipe in use collects more or less saliva which finds access to the stem and bowl of the pipe forming objectionable fouling.

40 In the present invention, 1 indicates the bowl of the pipe and the short stem usually made integral therewith is indicated at 2.

The stem which has the mouth piece, is indicated at 3 and may be made as usually 45 constructed or as I prefer, it may be made to have a straight underside.

The two parts of the pipe, to wit; the bowl stem 2, and the mouth stem 3, are joined by a member 5. As shown in the 50 drawing, this member has a centrally disposed projection 6, against which the ends of stems 2 and 3 may engage, while the portions of this member 5 on opposite sides of the projection 6 extend into the stems 2 and 55 3, having a snug fit which effectually serves to unite the three parts together.

The member 5 has formed, in which may be termed the top part thereof, a groove 7, which groove is open at the top except for a short distance upon both sides of the central projection 6. This portion of the groove just referred to is indicated at 8 and the construction insures that there will be no leak at the joint where stems 2 and 3 engage projection 6, a leak being very undesirable because of its effect on the draw of the pipe.

The provision of a construction with an open groove like groove 7 is advantageous as it permits the groove to be easily cleaned 70 of accumulated tobacco dust drawn back from the bowl in the use of the pipe. Furthermore having the groove 7 at the top of the member 5 provides a larger space in the mouth stem 3 for the accumulation of saliva, and in the stem 2 for tobacco dust and ash dust which may pass through the dust which connects the bowl with the stem 2.

The accumulated moisture in stem 3 may be discharged by inserting the pipe with 80 stem 3 down, or the stem may be removed.

At the end of the member 5 which is within stem 3, the groove 7 is directed downwardly at right angles, as indicated at 7^a and opens into a cup shaped portion at the 85 end of the member 5. This construction is more effective in preventing the entrance of collected saliva, into groove 7 than if the groove merely extended straight, to the end of member 5.

As will be seen, the general appearance of the pipe is not materially changed from the conventional shape and further, the use of the member 5 does not require a bulky or heavy construction for the pipe.

The construction is simple and the cleaning of the pipe is perhaps more simple and easier than the usual pipe.

Having described my invention, I claim: A pipe having a bowl with a short hollow stem, a mouth stem of hollow construction, a joining member coöperating with both of said stems, said member having an open groove in the upper portion thereof, one end of said groove being closed and a 105 downwardly directed opening coöperating with the groove at the closed end.

In testimony whereof, I hereunto affix my signature.

BENJAMIN F. JOHNSON
